UNITED STATES PATENT OFFICE

FRANK A. SCHUETZ, OF CHICAGO, ILLINOIS, ASSIGNOR TO THE ADLAKE COMPANY, A CORPORATION OF ILLINOIS

SIGNAL LANTERN

Application filed July 16, 1926, Serial No. 122,854. Renewed February 13, 1929.

The invention relates to signal lanterns such as are employed in the railway service by train and yard men, of the general type of the lantern shown in the patent to Hamm & Schuetz, No. 1,415,633, of May 9, 1922.

The object of the present invention is to provide improved means for admitting air to the burner and for holding the globe and staying the upper portion of the font.

The invention consists in a structure such as is hereinafter described, and is illustrated in the accompanying drawings in which

Fig. 1 is a detail side elevation of the lantern, some portions being broken away and some portions being shown in section;

Fig. 2 is a detail sectional view on the line 2—2 of Fig. 1; and

Fig. 3 is a detail section on the line 3—3 of Fig. 2.

The lantern comprises the usual guard frame 10, which may be of wire, the base ring 11 within which the font 12 is seated, the globe 13, the dome 14, and globe holder 15. Certain details as of the dome 14, globe holder 15 and the carrying bail being omitted as not being involved in the present invention.

The font 12 may be of any desired form of construction, being shown as having a body drawn from a sheet of tin and a top plate 16 which may be crimped over the top margin of the body portion and permanently secured thereto as by the use of solder.

The base ring may be of the usual form of construction, its upper portion 17 being of greater diameter than its lower portion, within which the font is seated, thereby providing a passage 18 for air entering the induction ports 19, for supporting combustion. The globe seat is of sheet metal and comprises an upstanding section 20 for enclosing the lower end of the globe, this section being overturned at its upper margin to hook over the upper margin of the base ring to which it may be permanently secured as by clinching.

Below the section 20, the holder is flanged inwardly as shown at 21 to provide a seat for the lower margin of the globe 13. An annular skirt 22 depends from the inner margin of section 21 of the globe seat and is preferably formed integrally therewith. This

skirt is of slightly greater diameter than the font 12 and extends below the top thereof, space being provided between the skirt and the font for the passage of air from the chamber 18. Instanding lugs 23, conveniently formed by indenting the skirt 22, engage the side wall of the font and prevent its vibration. The lower portion of the skirt 22 is flared outwardly as shown at 24 forming a funnel shape flange for directing air into the passage between the skirt and the font. For convenience of description the air supplied through the passages between the skirt 22 and font 12 will be termed the auxiliary air supply for the combustion chamber. The length of the skirt is immaterial providing it extends below the top of the font and terminate above air ports as 19. The skirt 22 is provided with an annular series of ports 25 in its upper portion, and above the top of the font and constituting what, for convenience of description, will be termed the ports for the main air supply.

Air entering the induction ports 19 is admitted into the body of the lantern thru the passage between the skirt 22 and the font and thru the ports 25. The two sets of currents entering the body intermingle and are directed toward the burner which, as usual, is located at the center of the top of the font. When the lantern is used in a high wind, the interference of these two currents will prevent the blowing out of the flame.

I claim as my invention:

1. In a signal lantern, a base ring having air induction ports; a font housed within the base ring and carrying a burner, a globe seat at the upper end of the base ring and having a depending annular ported skirt, such skirt being of greater diameter than the font and extending below the top thereof and forming with the side of the font a passage for air.

2. In a signal lantern, in combination, a ported base ring, a font inclosed within the ring and spaced therefrom to enclose an air chamber, and a ported wall, crossing the upper end of such chamber and extending downward adjacent to but spaced from the

side wall of the font and providing with the font wall a restricted air passage.

3. In a signal lantern, in combination, a ported base ring, a font inclosed within the 5 ring and spaced therefrom to inclose an air chamber, and a ported wall, crossing the upper end of such chamber and extending downward adjacent to but spaced from the side wall of the font and having a flaring 10 flange at its lower end, and providing with the font wall a restricted air passage.

4. In a signal lantern, in combination, a font, a ported base ring inclosing, and extending above the font and spaced apart 15 therefrom to form an air chamber, a closure for the air chamber comprising a vertical wall ported above the font and providing with the side wall of the font a restricted upwardly opening air passage.

20 5. A signal lamp having a combustion chamber provided with a burner, and an air chamber, the air chamber having a main connection with the combustion chamber to supply air to the burner, and also provided with 25 an auxiliary air connection with the combustion chamber disposed to discharge air across and diffuse the air supplied by the first mentioned connection.

6. A signal lantern comprising a combustion 30 chamber and an air chamber, a burner in said combustion chamber, the air chamber having induction ports, a closure separating the two chambers and providing air ports in intersecting planes for the passage 35 of currents of air flowing laterally inwardly and other currents flowing upwardly and intersecting the first named currents within the combustion chamber for diffusing the air as it enters the last named chamber, the in- 40 tersection of said currents being adjacent to the wall of the combustion chamber and spaced a material distance from said burner.

7. A signal lantern comprising a combustion 45 chamber and an air chamber, the combustion chamber having a burner therein but being otherwise unobstructed, the air chamber having induction ports, a main air passage for conducting air from said air chamber and discharging the same laterally into 50 the combustion chamber and an auxiliary air passage for discharging air upwardly into said combustion chamber, and intersecting the air passing through the auxiliary air passage within said combustion chamber at 55 points adjacent to the wall thereof and spaced from said burner.

In testimony whereof I affix my signature.
FRANK A. SCHUETZ.
